Specification for Design.

Patented May 17, 1921.

Application filed January 27, 1921. Serial No. 440,509. Term of patent 7 years.

To all whom it may concern:

Be it known that I, CRESTON W. Scott, a citizen of the United States, residing at Greenfield, in the county of Franklin and State of Massachusetts, have invented a new, original, and ornamental Design for Inside Micrometers, of which the following is a specification, reference being had

to the accompanying drawing, forming part thereof.

The figure is a side elevation of an inside micrometer, showing my new design.

I claim:

The ornamental design for an inside micrometer, as shown.
